GARDEN SEEDER

Walter Schrader, Garden City, N. Y., assignor to
American Soil Products Co., Inc., New York,
N. Y., a corporation of New York

Application February 25, 1944, Serial No. 523,825

2 Claims. (Cl. 229—17)

This invention relates to garden seeders of the hand type for use in planting of seeds.

One of the important features of the invention resides in a garden seeder which is formed from a single blank of paper which may be circumflexed into and held in conical form to provide a receptacle for a quantity of seeds for planting, the apex end of the conical receptacle having a discharge opening which may be opened and closed by the simple manipulation of overlapping portions of the flexed blank.

Another feature of the invention is to provide a garden seeder which is simple and inexpensive of construction, easy to manipulate, and disposable after a limited use without appreciable loss to the user.

Other features of the invention will become apparent as the following specification is read in conjunction with the accompanying drawing, in which,

Figure 1 is a top plan view of the blank from which my garden seeder is constructed, looking at the inner side thereof.

Figure 2 is a side elevational view of the garden seeder in position of use.

Figure 3 is a top plan view.

Figure 4 is an enlarged vertical sectional view on the line 4—4 of Figure 3, the dotted lines indicating the position of the parts when the discharge opening is closed.

Figure 5 is a horizontal sectional view on the line 5—5 of Figure 4.

Referring to the drawing by reference characters, the numeral 10 designates a blank of stiff flexible paper such as manila or kraft stock which is of an irregular shape having a curved edge portion 11 which merges into a substantially straight edge portion 12, the latter merging with the relatively short rounded edge portion 13 which latter portion merges with a straight edge portion 14. The curved edge portion 11 also merges with a straight edge portion 15, the latter merging with a relatively short curved edge portion 16 which completes the peripheral edge of the blank. Adjacent the central or mid portion of the blank 10 is a U-shaped slit 17, the leg portions of which extend toward the curved edge portion 13. The slit 17 defines a tongue 18, the same being scored lengthwise midway of its width as at 19. The blank 10 is further slit on the straight line 20, the inner end of the slit 20 meeting the right portion of the U-shaped slit 17 while the outer end of the slit 20 extends to the edge of the blank intermediate the edge portions 14 and 16. The

slit 20 divides the blank into two manipulatable end portions A and B.

In order to transform the blank 10 into a conical shaped body 21 as illustrated in Figures 2 to 5 inclusive, the operator grasps the blank adjacent the edges 13 and 15 and imparts an inward pressure thereto, causing the free end portion A of the blank to outwardly overlap the free end portion B thereof. This lapping of the portions A and B imparts circumflexion to the blank and places the same under tension to form the conical shaped receptacle body 21. When the portions A and B are in their fully lapped position, the curved edge 16 of the portion A 15 substantially registers with the rounded edge 13 of the portion B as best illustrated in Figures 2 and 3. It will be understood that the lapping portions are securely held by the thumb and forefinger of the hand of the operator to maintain 20 the shape of the body 21. During the circumflexion, the inner corner 21' of the portion B rides over the inner side of the portion A while the tongue 18 extends outward through a discharge outlet 22, which outlet is formed by the 25 opening caused by the displacement of the tongue 18, the latter being coextensive with the portion B. The tongue 18 is folded on the score 19 to form a trough shaped discharge spout 23.

Assume that the seeder device is in the position 30 shown in Figures 2 to 5 inclusive, wherein the discharge outlet 22 is open. Seed contained in the conical shaped receptacle body 21 will gravitate through the discharge outlet and down the inclined spout 23.

The discharge opening 22 may be enlarged to 35 control the flow of seeds by shifting the lapped portion B outwardly relative to the portion A while holding these portions between the thumb and forefinger. Also, the discharge opening 22 40 may be entirely closed by shifting the portion B inwardly toward the apex of the body relative to the portion A. Thus it will be understood that with the discharge opening closed, the conical receptacle body may be dipped into a bag of seed, carried to the prepared garden row to receive the seed, and by manipulation of the portion B relative to the portion A effect an opening of the discharge outlet to enable seed to gravitate therefrom down the spout 23.

By reason of the simplicity and inexpensive manner in which the seeder device is constructed, the same may be disposed of after limited use without economic loss to the user, and if desired, 55 suitable advertising indicia may be printed di-

rectly upon the blank 10 and the device given away for advertising purposes.

While I have shown and described what I consider to be the most practical construction of my invention, I wish it to be understood that such changes in construction and design as come within the scope of the appended claims may be resorted to if desired.

Having thus described the invention, what I claim as new and desire to secure by Letters Patent is:

1. A conical garden seeder device formed from a single flexible blank having a relatively long arcuate edge, a pair of converging side edges one of which extends from the arcuate edge, a relatively short arcuate edge connecting the converging edges, a substantially straight edge extending from the relatively long arcuate edge in converging relation to other of the pair of converging edges, a U-shaped slit provided adjacent the mid portion of the blank having its leg portions ex-

tending toward the relatively short arcuate edge, and a straight slit in said blank extending from the bight portion of the U-shaped slit to that one of the pair of converging edges which is arranged in converging relation to said substantially straight edge, whereby said blank may be manually formed into a conical body and outwardly displace the U-shaped slit portion thereof to provide a discharge opening in the apex end of the conical body by overlapping and gripping portions of the blank adjacent opposite sides of the straight slit.

2. A conical garden seeder device as set forth in claim 1 in which the portion of the blank defined within the U-shaped slit constitutes a tongue, and a fold score provided medially along said tongue lengthwise thereof to facilitate the forming of the tongue into a discharge spout when the same is displaced from the blank upon forming of a conical body.

WALTER SCHRADER.
